DIESEL ENGINE COMPANY, OF ST. LOUIS, MISSOURI, A CORPORATION OF MIS-
SOURI.

ENGINE REVERSE-GEAR.

1,352,717.

Specification of Letters Patent. Patented Sept. 14, 1920.

Application filed May 8, 1917. Serial No. 166,129.

To all whom it may concern:

Be it known that I, EUGEN ZBINDEN, a citizen of Switzerland, residing in Bern, Blumenbergstrasse 39, Switzerland, have invented the following described Improvements in Engine Reverse-Gears.

The invention relates to reversible internal combustion engines of the fuel-injected type, having starting and fuel valves and a valve gear-system with its control divided into two branches, one for changing over from air to combustion-running and for stopping, and the other for reversing; and it comprises a simple form of interlocking safety device and its combination with the valve gear system whereby the first control except when in neutral position bars the second against movement within the reversing limits, and the second, when within said limits, blocks the change from air to combustion running, or vice versa, the purpose being to guard against danger resulting from an improper sequence of the functions of the organization, as will be well understood.

The first branch of control has one fulcrum shaft for every cylinder or group of cylinders by which the valve gear of the said cylinder or group of cylinders is set to position "stop" or "air starting" or "combustion running." These three conditions correspond to a certain middle position of the shaft and to either one of two other extreme positions, the latter being to the right and the left of the said middle position.

The second branch of control is likewise rotatable on a fulcrum shaft and can be moved within a certain angle. Every position within two extreme sectors of the radius of the geometric axis corresponds to a certain cut-off and at the same time to a certain maximum lift of the valves thereby actuated. One of these sectors corresponds to the engine running forward, the other to the engine running backward. Consequently if the shaft is turned into such a position that the radius of the geometric axis passes from one to the other of the two sectors, the running of the engine is changed from forward to backward or vice versa. The object of the invention is to provide a device which prevents the second branch of control to move from the ahead sector to the astern sector as long as the

first branch of control is not in the "stop" 55 position. This device further prevents the fulcrum shaft or shafts of the first branch of control moving out of the "stop" position as long as the shaft of the second branch of control stands within the range of reversing limits.

The annexed drawings show two designs of this interlocking arrangement. They refer to valve gears of motors with two groups of cylinders, each of these groups 65 being provided with an independent first branch of control. Only the shafts of the two branches of control have been marked in order to make the diagram simple and clear.

Figure 1 is the side view of the design where the shafts of the two branches of control are arranged very near to each other.

Fig. 2 gives a front view of the design 75 of Fig. 1, showing it partly in section and with the second branch of control in the middle position.

Fig. 3 is a partial plan view.

Fig. 4 gives a side view of another arrangement where the shafts of the two branches of control are arranged at a greater distance from each other.

In these figures the two shafts of the first branch of control are marked by 6. 85 Each of these shafts 6 carries a hand lever 7 solidly fixed by a key. The levers may be put in position I (stop), II (air starting) and III (combustion running). 1 denotes the shaft of the second branch of control which is common to all the cylinders or groups of cylinders and is moved by means of hand wheel 2 and worm-gear 3 and 4 within the angle IV—VII. Sectors IV—V and VI—VII indicate the range of the two 95 regulating zones of which one corresponds to running forward, the other to running backward. Between radius V—VI lies the zones of reversing of the direction of rotation.

The cylinder marked 11 may be understood to represent one of the cylinders of a Diesel or similar type of engine, and the valve 12 its usual fuel injection valve. Such engines are started and operated, for maneuvering, by compressed air, and 13 represents the starting valve for the admission of the starting air at such times.

In the particular form of gearing for which the invention is more especially designed, these two valves are operated by rockers 14 and 14^a journaled on bearings 5 15, these bearings being arranged eccentrically upon the shaft 6, which may itself be turned in supports 16 or otherwise, by means of the handle 7 attached to it, for the purpose of shifting the fulcrum 10 axes of the rockers. In the position shown in Fig. 1 the axes of both rockers are out of operative relation to their respective valves so that neither of the latter is in action and the engine is consequently at rest or turning 15 over merely by its momentum. When the handle is moved to the position II, however, the rocker axes are shifted so that rocker 14^a may operate the starting valve, the fuel valve rocker being out of 20 action upon its valve, while movement to position III removes rocker 14^a from operating relation to the starting valve and brings rocker 14 into active relation with the fuel valve. 25 The drawings show the rockers as operated by a duplex cam mechanism comprising a pair of cams 17 and 18 for the fuel valve and a pair 17^a and 18^a for the air valve, the members of each pair being placed side 30 by side upon a cam shaft 19 and arranged to operate their respective valves through push-links 20 and 20^a, respectively. Each link carries two cam-rollers, for the pair of cams that operate it, one roller for each cam. 35 The active portions of the cams 17 and 17^a are so arranged with reference to the angular position of the cam shaft as to be suited for operating their valves in, say, a forward direction of engine running and the similar 40 portions of cams 18 and 18^a are arranged for the opposite direction, and for such purposes the cam-rollers 21 and 21^a occupy offset positions on their respective links, with respect to the rollers 22 and 22^a, so that 45 by swinging the link (on its pivotal connection with its valve rocker), either set of cam rollers may be brought into the range of action of its corresponding cams, the other set being simultaneously removed 50 from the range of its cams. Such swinging or shifting of the push-links is affected by the second rock-shaft 1, operated by the hand-wheel 2, as for instance through the worm 3 and worm segment 4, and connected 55 with the push-links 20, 20^a by arms 23, 23^a and pivotal links 24 and 24^a, respectively. The safety provisions include an arm 5 fixed to the rock-shaft 1 and having a locking portion 9 preferably directed outwardly 60 or perpendicular to the plane of its arc; and the member with which it co-operates to produce the desired interlock is a rotary gate or obstruction formed on or secured to each of the shafts 6, and being desirably constituted in the illustration, by the slotted or

notched end 8 of said shaft and disposed in the arc of movement of the contact or locking element 9. The parts are so proportioned and arranged that when the first control effected by handle 7, is in the engine stopping position of Fig. 1, the gate 8 allows the element 9 to pass freely by it or through the notch, while when said control is in either of positions II or III such movement is obstructed. Thus the second 70 control cannot be shifted from the position of forward running to astern or vice-versa, until the first control is brought to neutral. At all such times, however, the second control effected by hand wheel 2, may be operated to shift the contact member toward and from the barrier to an extent which, while insufficient to effect reversing, serves to vary the action of the valves in the manner already described. 80

Moreover, during the act of reversal of the push links, the locking element 9 being within slot 8, the first control is thereby blocked against movement and the handle 7 cannot therefore be moved from its neutral position until reversal has been completed. For this purpose the locking element 9 is made of suitable length as shown in Fig. 1. As soon as the arcuate projection 9 has disengaged from the slot, however, 95 the lever 7 may be operated as desired either for admitting fuel or air and in either case may be used to control the extent and duration of the valve opening. 95

In the modification of Fig. 4, wherein 100 similar parts are indicated with supercharacter "a", the locking element 9^a is mounted upon a rod 10 guided slidably in bearings 30 and constituting a jointed extension of the arm 5^a. The principles of construction and 105 operation, it will be apparent, are similar to those of the other embodiment.

What is claimed as new is:

1. In an internal combustion engine, the combination with valves serving for air-starting and combustion-running, respectively, valve gearing for operating the same, a first control active upon said gearing to cause the operation of one or other or neither of said valves, and a second control 110 for adjusting said gearing for forward or backward running, of a swinging contact member connected with the second control, and a rotary gate united with the first control and constructed to prevent operation of the second control within the reversing limits except when the first control is in neutral position and further to prevent the first control or parts thereof being turned into position "air starting" or "combustion 120 running" as long as the second branch of control is in the zone of reversing.

2. In an internal combustion engine, the combination with valves serving for air-starting and combustion-running, respec- 130

tively, of a suitable operating gear, two oscillatory controls and a safety device comprising a swinging arm connected with one of the controls and a rotary gate on the other 5 control adapted for mutually interlocking with the swinging arm to prevent joint operation.

3. In an internal combustion engine, the combination with fuel and starting valves, 10 a valve gear, means for setting said valves into and out of action comprising a shaft provided with a passage, a reversing shaft operative upon said valve gear, and an arm connected with said reversing shaft and 15 adapted to pass through said passage only when the first shaft is in neutral position and which prevents the shaft of the first control being turned out of its neutral position as long as a portion of the arm is in 20 mesh with the first branch of control.

4. In an internal combustion engine, the combination with fuel and starting valves, a valve gear, means for setting said valves into and out of action comprising a shaft 25 having a gate upon its end, a reversing shaft operative upon said gear, and an arm connected with said reversing shaft and having a laterally projecting locking member adapted to pass said gate only when the first 30 shaft is in neutral position and which prevents the shaft of the first branch of control being turned out of its neutral position as long as the interlocking portions are in conjunction.

35 5. In an internal combustion engine, the combination with valves serving for air-starting and combustion-running, respectively, and valve gearing for operating the same, of a first control operative upon said 40 gearing to cause the operation of one or other or neither of said valves, a second control for adjusting said gearing for forward or backward running, and an interlock constructed to prevent operation of the 45 second control within the reversing limits except when the first control is in the neutral position and further to prevent the first control or parts thereof being turned into position "air starting" or "combustion running" as long as the second branch of control 50 is in the zone of reversing.

6. In an internal combustion engine, the combination with valves serving for air-

starting and combustion-running, respectively, valve-rockers therefor, a starting, 55 combustion-running and stopping control shaft controlling the rockers, mechanism comprising duplex cams and cam-rollers for operating each of the rockers, and a second control shaft connected to shift the duplex 60 cam-rollers for forward or backward running, of means connected with the shafts for obstructing movement of said second control within the reversing limits except when the first control is in stopping position and 65 for preventing the first control being turned into position "air starting" or "combustion running" as long as the second branch of control is in the zone of reversing.

7. In an internal combustion engine, the 70 combination with fuel and starting valves, a valve gear, a divided control acting upon a portion of the valve gear to place said valves into and out of action, said control comprising two substantially alined shafts, 75 and another control shaft connected with the valve gear to effect reversal, of an arm connected with the reversing control operative between the proximate portions of the shafts, and gates upon said alined shafts, 80 both of which must be in neutral position to permit the passage of the arm.

8. In an internal combustion engine comprising a plurality of groups of cylinders, the combination with fuel and starting 85 valves for each cylinder, and valve gearing, of a divided control acting upon a portion of the valve gearing to place said valves selectively into and out of action, said control comprising a stopping, starting and 90 combustion-running shaft for each group of cylinders, another control shaft common to both groups of cylinders and connected with the valve gearing to effect reversal, and interlocking elements connected with the stopping, starting and combustion-running 95 shafts and with the common reversing shaft, respectively, whereby the said divided control may not be operated as long as the reversing shaft is in the zone of reversing and 100 whereby, further, the reversing shaft may be operated only when both shafts of the divided control are in neutral position.

In testimony whereof, I have signed this specification.

EUGEN ZBINDEN.
